John E. Kenney, Portland, Oreg.

Application March 8, 1938, Serial No. 75,654

Term of patent 7 years

To all whom it may concern:

Be it known that I, John E. Kenney, a citizen of the United States, residing at Portland, in the county of Multnomah and the State of Oregon, have invented a new, original, and ornamental Design for a Combined Air Conditioner and Ozonizer, of which the following is a specification, reference being had to the accompanying drawing, forming part thereof.

Fig. I is a side elevational view of a combined air conditioner and ozonizer showing my new design.

Fig. II is a top plan view; and

Fig. III is an end elevational view thereof.

I claim:

The ornamental design for a combined air conditioner and ozonizer, as shown.

JOHN E. KENNEY.
